DESIGN FOR A SOUVENIR PLAQUE

Harold A. McPeak, Wichita, Kans.

Application July 3, 1939, Serial No. 85,837

Term of patent 7 years

To all whom it may concern:

Be it known that I, Harold A. McPeak, a citizen of the United States of America, residing in Wichita, in the county of Sedgwick and State of Kansas, have invented a new, original, and ornamental Design for a Souvenir Plaque, of which the following is a specification, reference being had to the accompanying drawing, which forms a part thereof.

Now referring to the drawing,

I claim:

The ornamental design for a souvenir plaque, as shown.

HAROLD A. McPEAK.
